LUBRICATING DEVICE

Harry R. Tear, Evanston, Ill., assignor to The Lubrication Corporation, Chicago, Ill., a corporation of Delaware

Application September 25, 1935, Serial No. 42,000

2 Claims. (Cl. 221—47.3)

This invention relates to lubricating devices and more particularly to portable lubricant dispensers having a reservoir to contain a supply of lubricant.

5 Lubricant dispensers or grease guns of this type ordinarily have reservoirs or barrels which sometimes serve as containers for bulk lubricant and sometimes serve as mere protective housings for cartridges (factory filled packages 10 of lubricant). These barrels are usually constituted by shells made of thin steel tubing or sheet steel for lightness and strength and it is desirable to have one end of the shell detachable from the dispenser or gun or to provide 15 a detachable cap for the other end of the shell or both in order that the shell may be filled readily with bulk lubricant or that a cartridge may be inserted in the shell. It is also desirable to construct the detachable joint between 20 the shell and the gun and/or the cap so that these parts can be attached to and detached from one another quickly and easily.

Prior to the present invention these detachable joints have been formed either by cutting 25 fine screw threads in the ends of the shell or by pressing or rolling relatively coarse screw threads therein. If cut threads were used, they were necessarily very fine to avoid excessive weakening of the relatively thin shell, and the use 30 of fine threads in turn necessitated a large number of threads turned several complete revolutions into the joint to provide a firm joint. This led to several disadvantages in that it was extremely tedious to turn the shell or other part 35 through several complete revolutions each time the parts were attached or detached and in that the fine threads were found to be extremely liable to be damaged due to being struck when the parts were detached or due to becoming 40 crossed during interengagement of the parts.

Rolled or pressed threads were also unsatisfactory due to the axial length of shell required for their formation and to the weakness of the joint formed thereby, particularly in tension. 45 Another difficulty incident to either of these types of joints was that of forming a tight seal between the end of the shell and the gun and/or cap which is necessary in case the shell is filled directly with bulk lubricant or where air pressure is used to urge lubricant from a cartridge into the dispenser. Since the shell was quite thin it presented an end section too small to seat properly on a gasket.

One of the objects of the present invention 50 is to provide a lubricating device in which the

above-mentioned difficulties and disadvantages are eliminated.

It is another object of the invention to provide a lubricating device having a lubricant barrel in which the barrel can be quickly and easily attached to or detached from the device. 5

Another object is to provide a novel shell in which the end of the shell is protected and in which sealing may be effected readily.

According to one novel arrangement, a barrel 10 is provided constituted by a relatively thin tubular shell having fine screw threads at one end by which it is secured more or less permanently to a relatively heavy ring. The ring has coarse threads by which it is easily and quickly attached to a lubricating device and/or cap and 15 serves also to protect the end of the shell and to provide a large sealing area for engagement with a gasket.

Other and further objects, advantages and 20 novel features of the invention will appear from the following detailed description when taken in connection with the accompanying drawings which show several illustrative embodiments of the invention and in which:

Fig. 1 is a view of a lubricant dispenser embodying the invention with parts in section and 25 parts in elevation;

Fig. 2 is an enlarged sectional view of a connector;

Fig. 3 is a view similar to Fig. 2 showing a 30 modified construction; and

Fig. 4 is a sectional view of a lubricant shell with a cap attached thereto.

The dispenser of Fig. 1 is illustrated as of the power operated type constituted by a power device 1 to which a handle 2 is attached and a trigger 3 for controlling operation of the power device. The power device 1 may be of any desired type to be operated by any suitable medium such as compressed air or electricity, to a source 35 of which, not shown, the power device may be connected. A pump 4 is rigidly connected to the power device and has an outlet 5 which is adapted to be connected either directly or 40 through a flexible conduit to a suitable dispensing nozzle, not shown, for supplying lubricant to a point or points to be serviced.

The pump 4 receives lubricant through an inlet opening 6 formed in a connector member 7 which is rigidly attached to the pump. The connector 7 is formed with an inlet stud 8 which is of such a shape as to form a lubricant tight seal with a cartridge which supplies lubricant to the pump or on which is threaded a member 50 55

9 so shaped as to form a seal with the cartridge. The connector 7 is also formed with a depending cylindrical skirt 10 provided with relatively coarse internal screw threads and with a threaded lug 11 by which it is attached to the pump.

5 Lubricant is supplied to the pump from a lubricant cartridge 12 having an outlet opening 13 in one end thereof, the walls of which are shaped to form a lubricant tight seal with the member 9. The end of the cartridge 12 adjacent the outlet opening has a forwardly projecting flange 14 formed with lugs to make a bayonet joint with a connector plate 15 which is secured to the stud 8 as by being slipped over the stud 15 and clamped thereon by the member 9. The opposite end of the cartridge is closed by a slideable follower piston 16 which may be moved through the cartridge to urge the contents therefrom into the pump 4.

20 In order to inclose and protect the cartridge there is provided a barrel constituted by a cylindrical shell 17 closed at one end by a cap 18 and adapted to be connected to the skirt 10 at its opposite end. The cap 18 is permanently or semi-permanently attached to the shell as by screw threads and carries an air inlet valve 19 which is provided with a vent 20 adapted to be closed when the inlet valve is fully screwed into the cap but opened to vent air from the shell when 30 the valve is unscrewed slightly. The purpose of the air inlet valve is to place the interior of the shell under pressure to urge the piston 16 through the cartridge and it will be apparent that the valve 19 might be replaced by a compression spring, a manual feed rod, or other suitable means to urge the piston 16 through the cartridge.

35 According to the present invention the shell 17 is detachably connected to the skirt 10 through an annular ring 21 formed of relatively heavy material and permanently or semipermanently secured to the shell through fine screw threads. The exterior surface of the ring 21 is formed with relatively coarse screw threads for engagement with the internal threads on the ring 10 and, if desired, a sealing gasket 22 may be mounted in the connector 7 against which the end of the ring 21 seats. To remove the shell from the dispenser as in replacing the cartridge it is only necessary to unscrew the ring 21 from the skirt 10, the thickness of the ring permitting the use of coarse threads which provide a quick and easy attachment and detachment. Since the ring always stays on the shell it serves 55 to protect the end of the shell from damage and also provides a large surface to seat on the sealing gasket 22.

60 Figure 2 illustrates a slightly modified construction including a connector 23 having an inlet stud 24 and a threaded flange 25 for connection to a dispenser. The connector has an internally threaded skirt 26 to which is detachably secured an externally threaded annular ring 27, a gasket 28 preferably being arranged between the end of the ring and the connector. A shell 29 is secured to the ring 27 by fine screw threads and is adapted to contain bulk lubricant which can be discharged through the stud 24 and flange 25 into a dispenser.

70 In Figure 3 there is shown a further modification constituted by a connector 30 having an inlet stud 31, an outlet stud 32 and an externally

threaded skirt 33. An internally threaded annular ring 34 is detachably connected to the skirt 33 and seats against a gasket 35 which is held in place by an annular skirt 36. The ring 34 is secured to a shell 37 in a permanent or 5 semi-permanent manner as by fine screw threads.

Figure 4 shows an arrangement for attaching a cap to a shell and which may be used in conjunction with any of the previously described 10 arrangements for attaching the shell to a dispenser or with a shell which is more or less permanently attached to a dispenser. As shown, a cap 38 having an air valve 39 with a vent 40 therein is formed with an internally threaded 15 skirt 41, adjacent the inner end of which an annular gasket 42 is mounted. An externally threaded annular ring 43 is detachably connected to the skirt 41 to seat on the gasket 42 and has more or less permanently secured 20 thereto a shell 44 which may contain bulk lubricant or a lubricant cartridge. The cap 38 may be detached from the ring 43 without disturbing the connection between the ring and the shell, thus leaving the ring to protect the thin 25 edge of the shell.

30 While several embodiments of the invention have been shown and described, it will be apparent that many changes might be made. For example, the shell might be secured to the ring 30 by welding or brazing or a bayonet joint might be substituted for the coarse thread connection between the ring and the connector or the cap. It is, therefore, not intended that the scope of the invention shall be limited to the embodiments shown or otherwise than by the terms of the appended claims.

35 What is claimed is:

1. A lubricating device comprising, a pump having an inlet opening surrounded by an annular collar provided with coarse screw threads, and a barrel adapted to be secured to said pump and including a thin walled cylindrical shell, a cylindrical connecting ring of relatively thick section, one end of said ring and one end of said shell being connected by means forming a semi-permanent connection, the opposite end of the ring being formed with screw threads to engage the threads on the collar, and an annular sealing gasket carried by the collar in 45 register with the adjacent end of the ring to form a fluid tight seal between the collar and the ring.

2. A lubricating device comprising, a pump having an inlet opening and an annular collar surrounding the inlet opening, means spaced from said collar and forming therewith an annular gasket space, screw threads formed on the same side of the collar as said space, a sealing gasket in said space, and a barrel adapted to 55 be secured to said pump and including a thin walled cylindrical shell and a cylindrical connecting ring of relatively thick section, one end of the ring and one end of the shell being semi-permanently secured together and the other end of the ring being formed with screw threads to engage the screw threads on the collar, said last named end of the ring presenting a flat relatively wide annular surface to engage said sealing gasket and form a fluid tight seal therewith 60 when the parts are assembled.

65 HARRY R. TEAR.
